UNITED STATES PATENT OFFICE.

PETER F. GOEHRING, OF GUTTENBERG, NEW JERSEY.

AUTOMATICALLY-CONTROLLED PUMP.

1,068,122.

Specification of Letters Patent.

Patented July 22, 1913.

Application filed October 23, 1912. Serial No. 727,275.

To all whom it may concern:

Be it known that I, PETER F. GOEHRING, a citizen of the United States, residing at Guttenberg, in the county of Hudson and State 5 of New Jersey, have invented certain new and useful Improvements in Automatically-Controlled Pumps, of which the following is a full and clear specification.

This invention relates to means for automatically controlling pumps for periodically raising the pressure in fluid-dispensing systems and has for its primary object to provide suitable and efficient means which can be simply and durably constructed which 10 will be positive in its operation, and which will be economical in its consumption of power.

One of the objects of the present invention is to provide improved pump control means 20 which will cause the pump to operate for a predetermined length of time during which the pressure is raised in excess of that actually required and according to which method of operation the pump is operated 25 less frequently and with increased efficiency during each operation.

Another object is to make it possible to lengthen or shorten the duration of such period of running to meet the requirements 30 of different conditions under which the system is operated.

Another object is to provide simple and efficient means for varying the critical pressure point at which the pump is automatically started.

Other and further objects will appear in the specification and be specifically pointed out in the appended claims, reference being had to the accompanying drawings exemplifying the invention in its adaptation to a beverage dispensing system.

In the drawings, Figure 1 is a side elevation of a beer pump, embodying my improvements; Fig. 2 is an end elevation of 45 the same; Fig. 3 is a fragmentary detail in plan view; Fig. 4 is a wiring diagram. Fig. 5 is a fragmentary elevation of the adjustable Bourdon supporting means, parts being broken away and parts shown in section.

Referring more particularly to the drawings and to the embodiment shown therein, the pump comprises three cylinders 1, within which reciprocate pistons (not shown) to which power is transmitted by pitmen 2, 50 from a crank shaft 3, said crank shaft being

journaled in standards 4, rigidly mounted on a base plate 5. Keyed to the crank shaft 3 is a spur gear 6, with which meshes a pinion 7 keyed to the spindle 8 of a motor 9, the driving power in this embodiment being 50 electrically operated and controlled. Also keyed to the crank shaft 3 is a driving pinion 10 meshing with a bevel gear 11 of a short shaft 12, said shaft being journaled in a standard 13. Also keyed to the shaft 12, 65 is a pinion 14 meshing with a spur gear 15, which is keyed to a shaft 16. Rigidly mounted upon the gear 15 in a suitable manner to space it therefrom, is a rotary contact 17 having a cam-like periphery and with beveled edges extending around such periphery. As shown in Fig. 2, the cam-like contact 17 increases in radius in an anti-clockwise direction for a purpose to be presently made clear. Slidably engaging the 70 periphery of said cam 17, is a resilient contact 18, which is secured at 19 to the base block 20.

Projecting laterally from the standard 13, is a pivot pin 21, upon which is pivotally 80 mounted a trigger 22, which carries an arm 23 of insulating material, said arm 23 being provided with a pad 24 which is normally in position to hold the spring contact 18 away from the rotary contact 17 when the 85 smallest radius of the contact 17 is adjacent thereto. A spring 25 tends to maintain the arm 23 with the pad 24 beneath the contact 18 until such time when the pressure drops below the critical point. A 90 Bourdon tube 26 which is subject to the pressure produced by the pump, has its outer end connected to a link 27, which is pivotally connected to the trigger 22. Said outer end of the Bourdon tube 26 and the link 27 form in effect a toggle for operating the trigger 22. Thus when the pressure of the system drops, the parts assume the positions shown in dotted lines in Fig. 1, and the pad 24 is removed from under the upper extremity of the contact 18, permitting said extremity to engage the periphery of the rotary contact 17, at approximately its smallest radius. This closes the circuit and starts the motor 9. The contact 17 being constantly driven by the motor 9 by means of geared connections shown on the drawings, will continue its rotation for a complete turn or until the extremity of the contact 18 reaches the outermost or high point of the contact 17 105 110

when said contact 18 is permitted to drop inwardly toward the shaft 12. During this interval, however, the pressure has risen in the system and the arm 23 with pad 24 has 5 returned to normal position, this serving to separate the contacts 17 and 18 until the automatic release again occurs. At each operation of the pump, the pressure in the system is or may be raised considerably 10 above the critical pressure point at which the Bourdon tube causes the release of spring contact 18 and by means of the change gearing interposed between the crank shaft 3 and shaft 16 any definite and pre-determined amount of compression within cer- 15 tain limits can be obtained.

In order to provide simple and efficient means for varying the action of the Bourdon tube 26, said tube is mounted to be 20 moved vertically. For this purpose, a post 30 has secured thereto in any suitable number such as by brazing, spaced plates 31 which are provided with slots 33. Extending through the slots 33, are set screws 32 25 which are threaded into a lug formed on the Bourdon tube 26. A pointer 34 which moves up and down with the Bourdon tube, is adapted to register with a scale on one of the plates 31. A simple representation of a 30 wiring diagram is shown in Fig. 4, the motor armature 35 being in running contact with brushes 36. One of said brushes is connected by a line wire 37 with a spring contact 18', which has sliding contact with 35 the lateral face of the armature 35, and the other of said brushes is connected with spring contact 18 through field coil 38 and line wire 39.

What I claim is:

- 40 1. In a device of the character described, the combination with a pump, of a motor for driving said pump, a contact rotated by said motor, a second contact, and pressure operated means for controlling the movement of said second contact.
- 45 2. In a device of the character described, a pump, a motor for driving the pump, a rotatable contact geared to said motor, a contact movable into and out of engagement 50 with said rotatable contact, and pressure

operated means for controlling such movement.

3. In a device of the character described, a pump, a motor for driving said pump, a rotary cam-like contact geared to said motor, a spring contact adapted to slidably engage said rotary contact, a trigger adapted to hold said spring contact away from said rotary cam, and pressure operated means 55 for moving said trigger.

4. In a device of the character described, a pump, a motor for driving the pump, a rotatable contact geared to said motor, a contact movable into and out of engagement with said rotatable contact, and pressure 60 operated means for controlling such movement, said controlling means comprising a lever adapted to hold said movable contact, and a Bourdon tube for moving said lever.

5. In a device of the character described, a pump, a motor for driving said pump, a rotary cam-like contact geared to said motor, a spring contact adapted to slidably engage said rotary contact, a trigger adapted to hold said spring contact away from 65 said rotary cam, and pressure operated means for moving said trigger, said rotary cam being adapted to automatically disengage itself from the spring contact.

6. In a device of the character described, a pump, a motor for driving said pump, a rotary contact geared to said motor, a spring contact adapted to engage the rotary contact, a trigger normally holding said spring contact away from the rotary contact, and pressure operated means for operating said trigger.

7. In a device of the character described, a pump, a motor for driving said pump, a rotary contact, geared to said motor, a 70 spring contact, a trigger normally holding said spring contact away from the rotary contact, pressure operated means for operating said trigger, and means for adjusting the critical pressure point of said pressure 75 operated means.

PETER F. GOEHRING.
